KNITTING MACHINE NEEDLE

Clarence W. Minton, Nashville, Tenn., assignor to
 Morpul, Inc., Greensboro, N.C.
 Filed Aug. 10, 1959, Ser. No. 832,574
 2 Claims. (Cl. 66—123)

This invention relates to textiles, to the production thereof, and to the equipment employed in the knitting or manufacture of the same including articles of various kinds and of which hosiery is an example.

The invention more particularly includes a needle of the character employed with the conventional dial and cylinder type knitting machine used for making seamless hosiery.

Rib knitting has been performed on knitting machines employing both vertically and horizontally reciprocable needles mounted in grooves in the outer surface of the structures with which the needles are associated. Needles which operate horizontally have been mounted in radial grooves in a dial or plate and these needles cooperate with vertically reciprocable needles in the needle cylinder during the knitting operation and in which there is a transfer of the yarn from the dial needles to the cylinder needles. In the transfer of the yarn in this type of structure the dial needles are extended beyond the peripheral limits of the dial and the yarn is similarly extended in loops by the dial needles. The cylinder needles are projected upwardly into such loops to transfer the loops from the dial needles to the cylinder needles. It is desirable to have these loops of sufficient width that they will be certain to receive the cylinder needles.

It is an object of the invention to provide an improved knitting needle with structure to present an enlarged loop to facilitate transfer of the loops between the cooperating needles of the dial and cylinder as well as a needle that will temporarily flex or bend to produce such enlarged loop.

Another object of the invention is to provide an improved knitting needle which will normally be straight within the confines of the dial but which when extended beyond the margin of the dial its outer end portion will change its plane to provide an enlarged loop.

Other objects and advantages of the invention will be apparent from the following description taken in conjunction with the accompanying drawing wherein:

FIG. 1 is a fragmentary top plan illustrating one application of the invention;

FIG. 2, an enlarged fragmentary perspective of a portion of the dial and cylinder of a knitting machine;

FIG. 3, a plan view of the needle itself; and

FIG. 4, an end view thereof.

Briefly stated, the invention is an improved needle having a thin elongated body with a reduced portion at one end terminating in a hook. The needle is adapted to be located in radial slots in a dial and be projected and retracted. It is composed of flexible material and has a reduced intermediate portion. The outer or hook forming end of the needle is offset from the plane of the body of the same when the needle is in its projected or free position and in alignment with the body when in its retracted position within the receiving slot in the dial.

With continued reference to the drawing, the needle 10 of the present invention comprises a relatively thin body 11 having a reduced portion 12 at one end forming a shoulder 13 and an inclined portion 14 disposed between such shoulder and the reduced portion 12. The reduced portion 12 terminates in a hook 15 the opening of which may be closed by a latch 16 mounted by a pivot 17 in a slot 18 in the reduced portion 12. A recess 19 is provided in the body adjacent the shoulder 13 to accommo-

2

date a conventional knitting needle 20 mounted in a cylinder 21.

The needle 10 is reciprocably mounted in a dial 25 having radial slots 26 each of which has an enlarged cutout portion 27 at the periphery of the dial in which inclined surfaces 28 are provided with conical concave surfaces 29 directed inwardly toward the center of the dial.

The needle 10 is constructed from flexible material and is adapted to be twisted or warped in the area of the recess 19 so that the reduced portion 12 and the shoulder 13 are disposed in a different plane than the body 11 when the needle is projected from the dial. In order to project and retract the needle in the slots 26, the needle is provided with a butt 30 which cooperates with conventional cams (not shown) to move the needle in and out of the dial so that yarn 31 may be knit in the conventional manner.

In the operation of the device a loop of yarn is engaged by the shoulder 13 and extended beyond the limits 20 of the dial during the rib knitting process. When the loop of yarn is extended it is desirable to open or widen the loop so that the needle 20 carried by the cylinder 21 will be certain to enter the loop and prevent the dropping of a stitch. In order to widen the loop the needle 10 has its 25 outer end distorted out of the plane of the body 11 so that when the needle is projected beyond the periphery of the dial the end of the needle will assume a different angle than the body of the needle to open the loop. When the needle is retracted the portion of the needle 30 which was distorted will bear against the concave portion 29 of the dial slot 26 and as the needle is retracted further the distorted portion of the needle will return to the same plane as the body of the needle. The loop of yarn which was on the dial needle is transferred to the 35 cylinder needle 20 and as the dial needle is retracted the latch 16 which was opened to permit the yarn to be engaged by the shoulder 13 will be closed by the yarn and the needle retracted without the hook engaging the yarn.

It will be apparent that a needle is provided which will 40 open a loop of yarn to aid in the transfer of such loop from the dial needles to the cylinder needles during a rib knitting operation without the necessity of having separate attachments or without the necessity of modifying a conventional dial.

The novel dial needle of the present invention can 45 perform an additional function in making the welt at the top of stockings in which alternate stitches are engaged by the dial needles and retained thereon while the cylinder needles form a sufficient number of courses of stitches 50 to make the welt. Upon completion of the necessary 55 number of courses in the welt, the loops or stitches which have been held in the dial needles are transferred to the cylinder needles in the manner previously described. This structure avoids the necessity of having bits which are conventionally used in this type of machine to complete the welt.

It will be obvious to one skilled in the art that various 60 changes may be made in the invention without departing from the spirit and scope thereof and therefore the invention is not limited by that which is illustrated in the drawing and described in the specification, but only as indicated in the accompanying claims.

What is claimed is:

1. The combination of a dial of an automatic transfer 65 knitting machine and a series of flexible dial needles, said dial having a plurality of radial slots with their sides extending substantially parallel to the axis of said dial, each said needle comprising an elongated body and a reduced portion at one end of said body, said reduced portion forming a hook, a shoulder portion formed at the junction of said body and reduced portion, said shoulder be-

ing adapted for engaging yarn, said shoulder portion and said reduced portion being inclined to the plane of said body when said needle is projected from said dial, said slots having inclined surfaces formed at the outer end thereof for engaging and twisting said shoulder portion and reduced portion upon the retraction of said needle to place said reduced portion and shoulder portion in line with said body when said needle is retracted.

2. For use in an automatic transfer knitting machine having a cylinder and a dial with radial slots formed therein, said dial having camming surfaces at the outer ends of said slots; the improvement comprising a flexible action dial needle movable between projected and retracted positions, said needle comprising an elongated body and a reduced portion at one end of said body, said

5 reduced portion forming a hook, a shoulder portion formed at the juncture of said body and reduced portion, said shoulder portion being adapted for engaging yarn, said shoulder portion and reduced portion being offset from the plane of the body when said needle is projected from a slot; whereby, when said needle is retracted into a slot, a camming surface twists said shoulder portion and reduced portion to place said reduced portion and said shoulder portion substantially in line with said body.
